[57] CLAIM

The ornamental design for a wall shelf, substantially as shown and described.

DESCRIPTION

FIG. 1 is a perspective view of a wall shelf showing my new design;

FIG. 2 is a front elevational view thereof;

FIG. 3 is a side elevational view thereof taken from the right side of the wall shelf as viewed in FIG. 2; the left side of the wall shelf is a mirror image thereof;

FIG. 4 is a top plan view thereof;

FIG. 5 is a bottom plan view thereof;

FIG. 6 is a rear elevational view thereof;

FIG. 7 is an enlarged fragmentary elevational view of the wicker work shown in FIGS. 1, 2, 3, and 6.
